(57) **CLAIM**

The ornamental design for an herb heater, as shown and described.

DESCRIPTION

FIG. 1 is a top front right-side perspective view of an herb heater, showing the new design.

FIG. 2 is a front elevational view thereof.

FIG. 3 is a rear elevational view thereof.

FIG. 4 is a bottom plan view thereof.

FIG. 5 is a top plan view thereof.

FIG. 6 is a left-side elevational view thereof.

FIG. 7 is a right-side elevational view thereof; and,

FIG. 8 is a bottom front right-side perspective view thereof. The broken lines shown in the drawings depict portions of the herb heater that form no part of the claimed design.

1 Claim, 7 Drawing Sheets
